UNITED STATES PATENT OFFICE.

ALBERT C. Y. MACADAM, OF REVERE, MASSACHUSETTS.

PHOTOGRAPHIC-PRINTING APPARATUS.

No. 882,571.

Specification of Letters Patent. Patented March 24, 1908.

Application filed June 24, 1907. Serial No. 380,392.

To all whom it may concern:

Be it known that I, ALBERT C. Y. MACADAM, a citizen of the United States, residing in Revere, in the county of Suffolk and State 5 of Massachusetts, have invented an Improvement in Photographic-Printing Apparatus, of which the following description, in connection with the accompanying drawing, is a specification, like letters on the drawing representing like parts.

This invention has for its object the production of a novel photographic printing frame and mask coöperating therewith, whereby the opening in the mask or mat may 15 be adjusted with relation to the sensitized paper upon which the counterpart of the negative is to be printed, and also whereby the negative of whatever form may be adjusted after the mask has been adjusted so 20 that an adjustment of the mask having been made, it need not be interfered with or displaced during any final adjustments of the negative.

The frame herein shown as of peculiar construction is defined in the claims and so also 25 is the mask or mat.

Figure 1 represents the face of my improved printing apparatus with a mask and negative or film in operative position; Fig. 2 30 is a rear side view of the printing apparatus with the back board in place; Fig. 3 is a longitudinal section of the parts represented in Fig. 1 on the dotted line x—x.

Referring to the drawings, A represents a 35 frame which may be a piece of board having at two of its edges feet a. This frame has a central opening or space a' of a size sufficiently large in its width and breadth to receive the largest piece of sensitized paper or 40 card a^x that it is desired to print upon. This space is adapted to be closed during the printing operation by means of a back board herein shown as made in two parts b, b' united by hinges b², said parts having stops b³, b⁴, 45 preferably one of said parts as b' having two stops b⁵, b⁶. The stops b³ and b⁴ contact respectively with the back of the board at the ends of the space, while the stops b⁵, b⁶ contact with the board at the sides of the space. 50 Each part of the back board also has a spring C that is connected centrally therewith by a screw c', the ends of said springs engaging suitable cleats or other usual means c², c³ to thus lock the back board in position in the frame. 55 The face of the back board is covered with a cloth of some kind, and in practice when the

back board is in its working position its face occupies a position in substantial alignment with the face of the frame so that when the mask and negative or film are put in printing position they may be sustained by the back board.

The mask D shown, comprises preferably several pieces of paper, herein shown as two pieces d, d'. These pieces may be united 60 at their edges in any suitable way, as for instance by a binding d² of paper or cloth. Each of these pieces of paper is provided with an opening. These openings may be made in any part of the paper desired that 65 light may pass readily through both openings, one opening being preferably a little larger than the other, as for instance, opening 2 in the sheet d is a little larger than the opening 3 in the sheet d'.

That a negative or a film f may be held in the best possible manner by this mask, I prefer to provide the sheet d with a piece of glass d^x or other usual transparent material of sufficient thickness to maintain its surface absolutely smooth, and I lay this piece of glass or other material, preferably between the inner side of sheet d and the film, and secure the same thereto in any usual manner. With this mask, when the negative is 75 a film, the film will be laid upon the upper side of the sheet d' with its face down to cover the opening 3. This done I lay the mask upon the face of the frame with the opening 3 overlying the sensitized paper, 80 and with the back board out of the frame I position the mask so as to place the opening 3 of the sheet d' in any desired position, the position being variable according to the particular part of the sensitized paper or 85 card upon which it is desired to print whatever is shown on the negative, and having so adjusted the mask I turn into their operative position, as herein shown, the four springs 8 and place them in the position shown in Fig. 100 1 to securely maintain the mask in its adjusted position; then I adjust the negative so that any part of the negative that it is desired to print on the sensitized paper or card may be exposed to the light through the opening 3 in the sheet d'.

To adjust the negative after the springs referred to have been turned into position to maintain the mask in its adjusted position, I may, with my thumbs in the space of the 105 frame not then occupied by the back board, act upon the negative through the opening

3 and turn or move the same to bring the picture thereon into exactly the proper position with relation to the opening 3, and thereafter I turn the separate set of holding devices shown as springs 10 so that they act upon the outside of the mask in such position that the pressure is passed through the sheet *d* onto the negative and onto the lower sheet. After this the back board is inserted 10 in the space, preferably the part *b'* of the back board is inserted first and fastened, and then the part *b*. In this condition it will be understood that the face of the back board and the mask and film practically 15 contact with opposite faces of the sensitized sheet *a* and the apparatus is so set that the light may strike first the sheet *d* of the mask.

The feet are of decided importance for the reason that they guard the springs or holders 20 and prevent them from being displaced or bent when handling the frame.

I have illustrated the four springs or devices for holding both the mask and the negative, but my invention is not limited to 25 the use of four such springs, as I might use more or less and yet be able to hold securely the subjects being treated. In case the negative was a piece of glass, then the negative would be sustained upon the face of the 30 board, it being covered preferably with flannel or similar material, while the mask outside the opening therein would contact with the negative either at the top or bottom. In this last plan four of the springs 35 might be used to act upon the glass negative and hold it in its adjusted position, and then the others on the mask to maintain it in its adjusted position, whereby one or more printings or exposures from the same negative 40 may be made without re-adjustment of either mask or negative.

I have used the term "mask" herein as synonymous with mat, both terms being used by photographers.

45 Having described my invention, what I claim as new and desire to secure by Letters Patent is:—

1. In photographic printing apparatus, a

frame, and a mask combined with a plurality of sets of holding devices mounted on the 50 face of the frame, one set acting to hold the mask and the other set acting to hold the negative, whereby the mask and negative may be adjusted separately and confined in adjusted position.

55

2. In photographic printing apparatus, a frame, and a mask combined with a plurality of sets of holding devices mounted on the face of the frame, one set acting to hold the mask and the other the negative, whereby 60 the mask and negative may be adjusted separately and confined in adjusted position, said frame having feet at its side to guard the holding devices.

65

3. In photographic printing apparatus, a frame, a back board having stops to contact with the back of the frame, and a plurality of sets of spring holding devices pivotally mounted on the front of the frame to act upon and maintain in their adjusted positions both a mask and a negative or film.

70

4. In photographic printing apparatus, a frame, a two-part back board each part provided with stops and a spring, and a mask having an opening and adapted to sustain a 75 negative or film, combined with independent means mounted on the face of the frame to respectively maintain the mask and the negative or film each in their adjusted position whereby the negative or film may be 80 adjusted through the back of the frame after adjusting the mask and without interfering with the position of the mask.

85

5. A mask for a photographic printing apparatus, the same comprising two sheets, 85 each having an opening through which may be observed a negative located between said sheets, and in the line of said openings.

In testimony whereof, I have signed my name to this specification, in the presence of 90 two subscribing witnesses.

ALBERT C. Y. MACADAM.
